UNITED STATES PATENT OFFICE.

HERBERT W. OWEN, OF DOVER, NEW HAMPSHIRE.

SPINNING OR WINDING MACHINE.

1,119,310.

Specification of Letters Patent.

Patented Dec. 1, 1914.

Application filed November 22, 1911. Serial No. 661,798.

To all whom it may concern:

Be it known that I, HERBERT W. OWEN, a citizen of the United States, and a resident of Dover, in the county of Strafford and State of New Hampshire, have invented certain new and useful Improvements in Spinning or Winding Machines, of which the following is a specification.

This invention relates to machines for winding yarn or thread upon a rotating bobbin wherein means are employed for traversing the yarn or thread guide so as to build up the bobbin in the desired form. Such mechanisms usually constitute what are termed "ring spinning frames" and in operation form what is known in the art as warp or filling wound bobbins.

As well understood by those skilled in the art, the strain or "draft" on the yarn is dependent upon the weight of the "traveler", and with the same traveler, such strain or draft varies according to the diameter of the part of the bobbin being wound, or, in other words, the angle the yarn or thread makes with respect to the center of the spindle or bobbin. It is least when the yarn or thread is being wound at the largest part of the warp or filling wind, as at the base portion of the conical end; and is greatest when the yarn or thread is being wound at the smallest part of the conical end, which is usually the bare bobbin or spindle. For this reason it has been a common practice to change travelers for varying sizes and quality of yarn or thread. As the weight of the traveler governs to a large extent the amount of yarn or thread that can be placed upon the bobbin, it follows that the heavier the traveler, the greater the efficiency of the machine. Breakage of yarn or thread occurs most frequently when the strain or draft upon the yarn is greatest, that is when the yarn or thread is being wound at the smallest part of the conical end of the bobbin, consequently the strain or draft on the yarn at this point determines the permissible weight of the traveler in either the warp or filling wind.

In the formation of "filling wound" bobbins by spinning frames of usual construction and operation, the layers of yarn are wound in conical relation, and both the base and tip or end of the wound mass have been of substantially the same conical form. It is desirable, of course, to increase the amount of yarn in such filling wound bobbin, and in

case of bobbins for use in some types of looms, such for instance as filling replenishing looms, bunches of yarn have been formed near the base of the bobbin, but the formation of such bunches has necessitated the use of special and complicated mechanism which is objectionable.

The above general facts, which are well understood by those skilled in the art, being borne in mind, will better serve to make clear the aims and purposes of the present invention which, generally stated, are to provide a machine for spinning or winding with means whereby the strain upon the yarn is relieved thereby permitting the use of a heavier traveler, and wherein, when producing filling wound bobbins, a simple and efficient means is provided for the formation of a "bunch" and the wound bobbin made to contain an increased quantity of yarn.

These and other features of the invention will best be made clear from the following description and accompanying drawings of certain forms or embodiments of the invention, it being understood that the invention is not restricted thereto, but may be embodied in various other forms or constructions within the true scope of the invention, as defined by the claims.

Of the accompanying drawings,—Figure 1 is a front elevation of so much of a spinning machine as is necessary to illustrate my invention in one of its embodiments. Fig. 2 is a detail plan view of a bobbin, ring and traveler to illustrate the direction of the yarn when being wound on the bare bobbin. Fig. 3 is a detail elevation of the builder motion looking from the right of Fig. 1. Figs. 4, 5 and 6 are detail elevations to illustrate the building up operation. Figs. 7 and 8 are views similar to Fig. 1, illustrating a modification hereinafter described, said Figs. 7 and 8 showing the parts in different positions. Fig. 9 is a detail view similar to a portion of Fig. 8, but illustrating a further modification.

Similar reference characters indicate the same or similar parts in all of the views.

Referring first to Figs. 1 and 2, the spindle rail 15 supports the spindles in the usual manner, only one of such spindles being shown as at 16. The ring rail 17 carrying rings as at 18 for the travelers, such as shown at 19 is supported upon lifter rods, 110 one of which is shown at 20. The rocker 21 having a weight 22 to elevate the ring

5 rail has a rocker arm 23 from which a link 24 extends to another rocker arm for another lifter rod. The rocker arm is provided with the usual segment 25 having a bolt 26 to which is connected one end of the chain 27. Said chain 27 in the particular structure shown, is in three parts or sections, two sections of which are connected by a closed spring 28, the third section being connected to the second section by a swivel 29. The chain passes over a sheave 30, mounted in a yoke 31, the latter being mounted in bearings 32, carried by a bracket 33, supported by a fixed part of the frame. The extreme end of the chain 27 is connected at 34 to the lever 35 which is pivoted at 36 to the builder arm 37, the latter having a weight 38 and carrying a roll 39 which is actuated by the traverse cam 40. The lever 35 is provided with a curved bearing surface 41 for the roll 42 which is carried by the slide 43 having teeth 44 engaged by the worm 45 on shaft 46. Said shaft has a pick wheel 47 which is engaged by the actuating pawl 48. This general character of builder motion is well known so its operation need not be described herein.

30 One of the important features of the present invention is the fact that the connection between the builder motion and the rocker arm is elastic, such elasticity serving to relieve the strain or draft on the yarn, as will presently appear.

35 As hereinbefore noted, it is desirable to use a heavy traveler, because thereby a more compact and homogeneous wound bobbin can be produced. The weight of the traveler, however, must depend upon the capacity of the yarn or thread to resist rupture when 40 subjected to its maximum strain or draft which occurs at the conical end of the windings or when the yarn or thread leads nearest to the axis of the bobbin or spindle. At or about this point in the conical wind the 45 ring-rail changes direction of movement, and, it may be, the rate of travel of the yarn or thread is changed owing to the change in diameter of the windings themselves when the rotation of the bobbin remains uniform. 50 The present invention contemplates means for relieving any sudden change or increase in the strain or draft upon the yarn at this and other time by the provision of the elastic section in the connection between the 55 builder motion and the rocker arm. This feature of the invention, in the illustrated form thereof, is secured by a spring 28 the coils of which are preferably closed upon each other in normal operation of the machine, but capable of separation under the action of sudden strain, thereby enabling a heavier traveler to be employed without danger of rupturing or breaking the yarn or thread. This structure results in making the 60 ring-lifting mechanism responsive to the

ordinary transmission of the builder motion during the formation of the wound bobbin and sensitive in relieving the yarn or thread from sudden change in strain or draft when the latter is at or about its maximum. The 70 particular reason for employing a spring the coils of which are normally closed, is to provide a limit beyond which the recoil or shortening-up effect of the connection between the builder motion and rocker arm 75 cannot act, but as obvious to those skilled in the art, this effect may be otherwise accomplished.

Figs. 4, 5, and 6 illustrate the bobbin *a* with the cone base *b* which gives to the bobbin base a more full and rounded form than is presented at the tip or top of the filling wound bobbin.

In the operation of the present machine, the cone base portion *b* is first wound by 80 traversing the ring-rail to a less extent than the normal traverse; and preferably, during the winding of the portion *b*, the traverse gradually increases, so that when the portion *b* is completed, the traverse of the ring- 90 rail has reached normal and preferably continues this to the end of the bobbin, it being understood, of course, that as the ring-rail is thus traversed it is gradually raised through the action of the builder motion, as 95 will more fully appear.

In order that the bunch may be shortened as indicated in Fig. 6, and still contain as much yarn as usual, resulting in providing a better form of bunch, I provide means for 100 reducing the traverse, the machine being operated at usual speed during the building of the bunch.

Referring to Fig. 9, connections between the builder motion and the rocker arm are 105 different from the direct chain shown in Fig. 1, although also including a spring. In said Fig. 9, a short length of chain 51 is connected to the rocker arm bolt 26, the other end of the chain being connected to 110 a yoke 52 in which is mounted a pulley 53. A chain 54 is connected at one end to the swivel 29 and passes around said pulley 53 and at the other end is connected to one end of a closed coil spring 55, the other end 115 of said spring being connected as at 56 to a link of the chain 54. This chain 54 and its spring 55 constitute a loop within which is mounted the pulley 53. Connected at 66 to the chain 54 adjacent the spring 55 is 120 a chain 65, the other end of which is adjustably connected to a suitable fixed bracket 67. With this structure when the rocker arm moves to the right from the position shown in Fig. 9, the chain 65 slacks up and 125 the rocker arm moves to the full extent during the traverses above the bunch. But all movements that are imparted to the rocker arm by the builder motion during the building of the bunch (these, of course, being 130

while the rocker arm is to the left of the position shown in Fig. 9) are by this form of the invention reduced one half because the taut chain 65 holds the point where it is attached to the chain 54 stationary, and the spring 55 expands and contracts as the builder motion chain section 27 alternately pulls and gives up. The loop around pulley 53 of course thus lengthens and contracts and causes the pulley 53 and chain section 51 to move one half the distance that is imparted to the chain section 27 by the builder motion during the building of the bunch. Consequently the traverses of the ring rail 15 are one half as much as usually imparted, and the result is that short, close-built bunches are formed, as indicated at *b* in Fig. 6, in comparison with Figs. 4 and 5. As the builder chain lets out, the change is gradual to a full-length traverse. In other words, during the building of the bunch or initial portion at the base of the bobbin, the ring-rail performs its traverse adjacent to the bobbin base, at which time the chain 65 acts through the spring to move the run of chain loop about pulley 53 as the chain section 27 through the builder motion moves to the left from the position indicated by Fig. 9, for instance, and back again, thus at such time the pulley 53 acts as a movable pulley, decreasing the traverse of the rail to one-half of what it would be were the chain 65 always slack. As the bunch or initial base portion of the bobbin is formed, the successive traverses of the ring-rail gradually become greater, because the builder motion causes gradually less and less drop to the ring-rail, so that chain 65 acts less and less upon the loop about pulley 53, with the result that when the bunch or initial portion of the bobbin has been completed, the builder motion will not cause the rocker arm 23 to move to the left sufficiently to permit the chain 65 to act upon the loop and the normal traverse of the ring-rail will be reached and continued to the top of the bobbin.

Instead of employing a straight chain section 65, I may provide a chain 58 (Figs. 50, 7 and 8) connected as by a link 57 to the end of looped chain 54 where the latter is connected to the spring 55, said chain 58 being in the form of a loop in which is a pulley 59. The other end of the chain 58 is connected as at 60 to the rocker arm 23. It is to be understood of course that the movement of arm 23 to the left for each traverse stops at a point in advance of the last preceding stop, in order to cause the successive traverses of the ring rail to be in higher planes. During the highest traverses the looped chain 58 is ineffective and is slack. But during the lower traverses, the looped chain 58 performs the same function as the chain 65 in Fig. 9, but acts quicker owing

to the looping of the chain around the pulley 59. To avoid overlaying the first traverses of the bunch resulting from the use of the construction shown in Figs. 7, 8 and 9, I provide means for letting out the builder 70 chain faster at the beginning of the spinning operation.

Referring to Fig. 3, it will be seen that I provide the lever 35 with a steep incline from the point *x* to the point *y* over which 75 the roll 42 rides during the building of the bunch. While the slide 43 is shifting to carry the roll 42 beyond the point *y*, the traverses above the bunch are being effected. As the roll travels from point *x* to point *y*, 80 the builder chain will be let out much more rapidly than after passing beyond point *y* as will be evident from Fig. 3.

The structures illustrated in Figs. 7, 8 and 9 provide for increased efficiency by 85 employing a pulley leverage that will provide a sensitive structure to bring less strain upon the elastic connection.

The cone-shaped-base bobbin commonly used for the "filling wind" is not entirely 90 satisfactory, because of the small amount of yarn that can be wound thereon, yet it has come into almost universal use for several reasons such as because the spinning breaks are reduced, the yarn is more readily removed from the bobbin, and because a more symmetrically perfect bobbin is formed. My present invention enables me by the simple addition of a hold-back connection in the manner shown, to more easily form the 100 bunch or cone base of yarn wound upon a straight bobbin. Moreover, this formation of the bobbin is ideal for looms having the well-known feeler attachment, because the waste of yarn is reduced to a minimum. 105

As hereinbefore mentioned, my improvements are not necessarily limited to the specific type of winding machines, known as spinning frames, as it is obvious that a machine similar to the one illustrated, but not 110 providing for imparting a twist to the yarn or thread would be properly called a winding machine.

I claim:—

1. A machine of the character described, 115 comprising a builder motion, a rocker arm, motion transmitting connections between the builder motion and rocker arm, said connections including a spiral spring variable in length and interposed in the length of 120 said connection for preventing excessive strain upon the yarn as it is wound to form the conical end portion of the wound bobbin.

2. A machine of the character described, 125 having means for rotating a bobbin, a guide for the thread to be wound on said bobbin, means for traversing the guide, a builder motion, a rocker arm, and a normally contracted elastic connection between said builder motion and rocker arm, said elastic 130

- connection being permanently free to permit it to vary in length.
3. In a spinning machine, the combination with the builder motion and the rocker arm thereof, of a flexible connection between said builder motion and arm, and a spring included in said connection, said spring having its ends joined to said connection at separated points and being permanently free to permit the connection to vary in length.
4. In a spinning machine, the combination with the builder motion and the rocker arm thereof, of a flexible connection between said builder motion and arm, said connection including a yielding loop, and a pulley in said loop, said pulley being connected to the rocker arm.
5. A spinning machine having variable connections between the builder motion and the ring-rail traversing mechanism, said connections being adapted to reduce the action of the builder motion transmitted to the traversing mechanism during the building of the bunch, the builder motion including means for letting off with increased speed during the building of the bunch.
6. A spinning machine having variable connections between the builder motion and the ring-rail traversing mechanism, said connections being adapted to reduce the action of the builder motion transmitted to the traversing mechanism during the building of the bunch, the builder motion including a slide having a roll, and a lever with which said roll co-operates, said lever having a relatively steep incline over which the roll travels during the building of the bunch.
7. In a machine of the character described, the combination of a series of spindles, a ring-rail having a series of rings and travelers for directing yarn to be wound upon the spindles, a builder motion and connections between it and the ring-rail for reciprocating the ring-rail in a direction longitudinally of the spindles, said connections including a spring the ends of which are connected at separated points of said connection for relieving the strain of the traveler on the yarn as the direction of the ring rail movement is reversed.
8. In a machine of the character described, the combination of a series of spindles, a ring-rail having a series of guides for directing yarn to be wound upon said spindles, a builder motion, and an extensible normally contracted connection between the builder motion and ring-rail.
9. In a machine of the character described, the combination of a series of spindles, a series of guides for directing yarn to be wound upon said spindles, a builder motion, connections between the builder motion and said series of guides to reciprocate the latter longitudinally of the spindles,
- said connections including a normally contracted spring for relieving the strain upon the yarn as the direction of movement of the guides is reversed.
10. In a machine for winding yarn in conical layers, the combination of a series of spindles, rings and travelers for directing the yarn to said spindles, a builder motion for traversing said rings and travelers lengthwise of the spindles in the formation of the conical layers, and means including a spring the ends of which are connected at separated points to said connection, acting as the yarn is wound on varying diameters of the conical wind to relieve the strain upon the yarn that a heavier traveler may be employed.
11. In a machine of the character described, the combination of a series of spindles, a series of guides for directing yarn to said spindles, a rocking device for moving the guides lengthwise of the spindles, a builder motion for actuating said rocking device, connections between the builder motion and said device, and a spring the ends of which are joined at separated points of said connections between the builder motion and said device acting automatically during the operation of the machine to change the length of traverse of the said guides during the building of a bunch.
12. In a machine of the character described, the combination of a series of spindles, a series of guides, a builder motion for imparting to said guides traverse movements lengthwise of the said spindles, connections between said builder motion and said guides including a loop having an elastic portion, a device about which the loop is passed, and means acting upon the loop during the operation of the machine to change the traverse of said guides.
13. In a filling winding machine, a series of spindles, a traversing mechanism, and a builder motion, permanently operable variable connections between the traversing mechanism and builder motion, and means acting automatically on said connections between the traversing mechanism and builder motion for causing said connections to impart a short traverse to said traverse mechanism during the formation of a bunch and thereafter to impart a longer traverse during the remainder of the winding operation.
14. In a machine of the character described, the combination of a builder motion and traverse mechanism, and a flexible connection between said builder motion and traverse mechanism including a flexible loop connected to one of said parts, said loop having a yielding portion.
15. In a machine of the character described, the combination of a builder motion and traverse mechanism, a flexible connec-

tion between said builder motion and traverse mechanism including a flexible loop connected to one of said parts, said loop having a yielding portion, and means acting upon the yielding portion of said loop to vary the movement of the traverse mechanism during the winding operation.

16. In a filling winding machine, the combination of a traverse mechanism and builder motion, a flexible connection between said parts for transmitting motion, a loop in said flexible connection, a pulley connected to one of said parts and embraced

by said loop, a spring in one run of the loop, and means connected to that run of the loop 15 for expanding the spring during a portion of the winding operation and leaving it unexpanded during the remainder of the operation.

In testimony whereof I have affixed my 20 signature, in presence of two witnesses.

HERBERT W. OWEN.
